Attorneys.

UNITED STATES PATENT OFFICE.

MARSENA R. JULIAN, OF BIRMINGHAM, ALABAMA, ASSIGNOR TO JULIAN SIGNAL COMPANY, OF BIRMINGHAM, ALABAMA, A CORPORATION OF DELAWARE.

BLOCK-SIGNAL SYSTEM.

1,232,561.

Specification of Letters Patent. Patented July 10, 1917.

Application filed April 8, 1913. Serial No. 759,817.

To all whom it may concern:

Be it known that I, MARSENA R. JULIAN, citizen of the United States, residing at Birmingham, in the county of Jefferson and

5 State of Alabama, have invented certain new and useful Improvements in Block-Signal Systems, of which the following is a specification.

This invention relates to cab carried block 10 signal mechanisms, the primary object of my invention being the provision of suitable mechanisms which may be carried in the locomotive cab, together with suitable contact shoes for coöperation with track contacts of 15 a block signal system.

The primary object of this invention consists in the provision of a signaling mechanism of the above described type, together with a co-acting signal recording mechanism, which may be employed with a block 20 signal system of any type in which both caution and danger contact shoes are employed, together with block clearing shoes.

A still further object of the invention is 25 to provide mechanism contained within the cab of an engine, or in any other suitable position upon a train, adapted to make electrical connection with the track signal system heretofore referred to, and adapted 30 when this connection is made to display a visual clear signal, cautionary signal or danger signal, and simultaneously energize a clear bell signal, a cautionary bell signal or a danger bell signal.

35 A further object in this connection is to provide means whereby upon the receipt by the cab mechanism of a cautionary signal, mechanism will be started to open the air valve of the brake system to put on the 40 brakes, and whereby upon the receipt of a danger signal said mechanism will also be started, means being provided however whereby the engineer may return the parts to a normal position after the receipt of the 45 signal, thus preventing the stoppage of the train.

A further object is to provide means whereby the various signals above referred to and the time of their receipt may be indicated upon a registering tape so that a record may be kept of all signals received by the engineer and thereby of the condition of the block.

50 A further object is to provide an electrically operated mechanism disposed within

the cab of the engine whereby cautionary or danger signals indicating whether or not the block is clear may be received within the cab and registered.

Other objects will appear in the course of 60 the following description.

My invention is illustrated in the accompanying drawings wherein:

Fig. 1 is a side elevation of a tender 65 and one of the switch engaging contact shoes thereon.

Fig. 2 is a plan view of the signal operating and recording mechanism located within the cab of an engine.

Fig. 3 is a section on the line 3—3 of 70 Fig. 2.

Fig. 4 is an end elevation of the construction shown in Fig. 2.

Fig. 5 is a perspective detail view of one 75 of the contact slides.

Fig. 6 is a perspective view of a contact slide coacting with the contact slide shown in Fig. 5.

Fig. 7 is a fragmentary vertical section on the line 7—7 of Fig. 4 showing the parts in 80 one position.

Fig. 8 is a like view to Fig. 7 but showing the slides depressed.

Fig. 9 is a fragmentary vertical section 85 on the line 9—9 of Fig. 4.

Fig. 10 is a perspective detail view of the danger slides and the replacing lever, the slides being shown separated.

Fig. 11 is a fragmentary vertical section 90 on the line 11—11 of Fig. 4.

Fig. 12 is a perspective detail view of the clearing slide and a portion of the replacing lever.

Fig. 13 is a perspective view of the automatic replacing lever and its actuating 95 mechanism.

Fig. 14 is a diagram of the wiring for the signal actuating and recording devices shown in Fig. 11.

Fig. 15 is a detail plan view of the mechanism for actuating the brake valve shaft.

Fig. 16 is a face view of a portion of the signal recording tape.

Corresponding and like parts are referred to in the following description and indicated in all the views of the accompanying drawings by the same reference characters.

The apparatus mounted upon the cab of the engine whereby the circuit is completed from the various shoes of the engine,

through the signal bells and signal lights to the ground is illustrated in Figs. 1 to 14. The shoes whereby a contact is made with the contact switches need not be specifically referred to as they may be made in many different forms and without departing at all from the spirit of the invention. The engine is, of course, provided with the ordinary air brake valve, but in addition thereto 10 a valve motor is provided which when a danger as well as a cautionary signal is sounded starts to operate and throws the air brakes on.

Referring now to Figs. 2 to 4, 78 designates a base upon which the mechanism is mounted, the mechanism being preferably inclosed within a case 79. Mounted within the case 79 are a plurality of pairs of electromagnets 80, 81 and 82. These magnets 20 are connected up as will be later described.

Mounted upon an upstanding bracket 83 are a plurality of armature levers 84, 85 and 86. These armature levers are all constructed in practically the same manner and 25 the levers are normally forced upward by means of springs 87. The lever 84 is the closing lever, that is, the magnets 80 are energized when the train enters the block, thus actuating the lever 84. The lever 84 carries at its end a pivoted dog 88 as does the lever 85. The lever 86, however, does not carry any dog.

Supported immediately in front of the levers 84, 85 and 86 is a frame 89. This 35 frame is metallic and is rectangular in form, the frame being bolted or otherwise attached to the non-conducting base 78. Carried upon one side of the base or formed with it is a stop 90 which engages with the lever 84 40 to limit its upward movement. The dog 88 on the lever 84 moves downward between guides 91 and 92 also carried upon the side of the frame.

Extending across the frame is a cross bar 45 93 as illustrated in Fig. 4, and disposed in the space between this cross bar and the top 89' of the frame 89 and against the inside face of one of the upright side pieces of the frame is a slide 94 which at its upper 50 end is provided with an inwardly extending lip 95 and at its lower end with an inwardly extending flange 96, the lip and flange being perforated as at 97 and the flange being also perforated as at 98 for the passage of certain guide rods later referred to.

This slide 94 is provided on its rear face with an outwardly projecting lug or shoulder 99, and attached to this slide is an outwardly projecting arm 100 composed of insulating material carrying a wedge-shaped contact member 101. Mounted inward of the slide 94 is a slide 102 formed at its upper end with the flange 103 and at its lower end with the outwardly extending lip 104. 65 The flange 103 and the lip 104 are perforated

as at 105 and the flange 103 is perforated as at 106.

Extending upward from the cross bar 93 to the cross piece 89' of the frame are a pair of guide bars 107. These guide bars 107 pass through the perforations 97 and 98 of the slide 94 and through the perforations 106 and 105 of the slide 102. It will be seen that the slide 102 is shorter than the slide 94 and is disposed interiorly of the same and that the slide 102 is independently shiftable vertically with relation to the slide 94. 75

The slide 102 is formed on its rear face with a pair of ratchet teeth designated 108 and 108^a, and the forward edge of the slide 80 102 is formed with a shoulder 109 and a ratchet tooth 109^a.

The dog 88 is adapted to engage with the teeth 108, 108^a, and a pawl 110 which is attached to the frame in any suitable manner 85 and extends downward therefrom is adapted to engage the teeth or shoulders 109, 109^a. When the slide 94 is in a raised position, as illustrated in Fig. 7, a spring pawl 111 is adapted to engage under the shoulder 99 so as to hold the slide 94 in a raised position. It will be noted, however, that the spring pawl 111 is sufficiently wide so as to extend over in the path of movement of the ratchet teeth 108 and 108^a, and that upon a full depression of the slide 102 by two actuations of the lever 84 as will hereafter more plainly appear, the tooth 108^a will engage the pawl 111 and force it outward, thus permitting the slide 94 to be drawn downward by means of a spring 112 which is attached to the arm 90 and to base or frame 89. 95

The lug 100 carries upon it the wedge-shaped head 101 which is of conducting material, and the wedge-shaped end of this head coacts with two spaced contacts 113 and 114 when the slide 94 is in a depressed position. When the slide is in a raised position, however, the metallic head 101 coacts with a contact strip 130 which is in circuit with the white light as will appear more fully in the diagram, Fig. 14. 100

The contacts 113 and 114 are respectively connected in a circuit leading to the green or cautionary light and the cautionary bell signal, and a circuit leading to the brake motor as will be later described. It is to be understood that the frame 89 is connected to the headlight generator or any other source of suitable electrical energy. 115

The means whereby the slides 94 and 102 are raised after having been depressed by the actuation of the lever 84 will be described later.

Mounted upon the opposite upright 89^a 125 of the frame 89 is a slide 115 (see Fig. 10) having the inwardly turned or flanged ends 116 which are perforated at opposite points for the passage of guide rods. This slide 115 is provided with an outwardly project-

ing arm or lug 117 carrying upon it a contact head 118. This head is, of course, of metal as is the slide 115 and the lower end of the head is beveled.

5 Mounted interiorly of the slide 115 is the slide 119 outwardly turned or flanged as at 120 at its lower end and as at 121 at its upper end. This flange 120 is provided with two perforations for the passage of guide rods, while the flange 121 is provided with one perforation. The guide rods 122 are attached in any suitable manner to the frame and pass up through these perforations in the flanges 116, 120 and 121 so that the slides 115 and 119 have free sliding movement. The slide 115 is urged downward by means of a spring 123 while the slide 119 is urged upward by a spring 124.

10 Forming part of the slide 119 is the projecting arm 125, the upper edge of which is flanged as at 126 for engagement by the extremity of the lever 86, as illustrated in Fig. 2.

15 The rear edge of the slide 115 is formed with a notch or shoulder 127, and the rear edge of the slide 119 is formed with a like notch 128. Coacting with these notches is a spring pawl 129 attached to the base in any suitable manner and acting to hold the slide 115 in its raised position. This pawl is sufficiently wide so that upon a descent of the slide 119, the beveled or rounded shoulder 128 will engage the pawl to shift it outward so that the spring 123 will draw the slide 115 downward.

20 The head 118 is adapted to engage in its raised position with a contact member 130 which corresponds to the contact member 130 previously referred to. This contact member 130 is electrically connected as will be later described.

25 Disposed immediately below the head 118 are the spaced contact members 131 and 132 which are insulated from each other and normally out of electrical engagement. When, however, the head 118 is depressed, it enters between the two contacts 131 and 132 and electrically connects them with the frame 89. One of these contact members, as 30 the contact member 131, is connected to a constantly ringing bell and a red signal light, and the other contact member 132 is electrically connected to the brake motor as will hereafter appear.

35 Mounted upon guide rods 133 extending down through the middle of the frame is a slide 134 as illustrated in Fig. 12. This slide at its forward edge is formed with a pair of ratchet notches 135 and at its rear edge 40 is formed with a shoulder 136. The pawl carried on the end of the clearing lever 85 is adapted to engage the notches 135, while the spring pressed detent or pawl 137, mounted upon the upper frame bar 89' is adapted 45 to engage the shoulder 136. This slide 134

is primarily for the purpose of recording the clearing signal and hence the parts are not connected to any signaling mechanism such as the lights or bells. The recording mechanism will be described later. Suffice 70 it to say that the slide 134 carries upon one side the outwardly projecting arm 215 having downwardly extending needles or punches 213 and 214. The slide also carries a downwardly projecting spring contact finger 140 and the slide 102 also carries upon it the downwardly projecting spring contact finger 141.

75 For the purpose of elevating the slides 94 and 115 after they have been depressed, 80 I provide the lever 142 which projects out toward the engineer and is connected to a rock shaft 143 mounted in suitable bearings upon the brace 93. The ends of this rock shaft are angularly bent as at 144, and project beneath the flanges 96 and 116 respectively. The lever 142 is held in its raised position by any suitable means as by the spring 145. When the lever is depressed, the arms or terminal ends 144 will rise, lifting 90 the slides 94 and 115.

85 Means must also be provided for automatically lifting the slides 102 and 119 after a predetermined time has elapsed from the moment at which they were actuated, as 95 will more fully appear in the description of the operation of this mechanism. This means includes a relatively small electrically actuated motor connected to gearing and a lever operatively engaged by said motor after the motor has operated from one predetermined position to another.

90 Referring to Fig. 13, 146 designates a vertical shaft supported in any suitable frame and carrying upon it the toothed wheel 147. 105 The motor comprises a pair of magnets 148 and an armature lever 149 pivotally mounted at its end as at 150. Carried upon the end of the armature lever but insulated therefrom is a pawl 151 which engages with the wheel or disk 147. A spring member 152 projects from the armature lever and bears against a contact screw 153. The lever 149 is connected by means of a conductor wire 154 with the magnet coils. One of the magnet wires 156 extends to a contact member 157 which is engaged by the depending contact finger 141 on the slide 102. The depending finger 140 on the slide 134 engages 110 with a contact member 158 which is also connected in circuit with said magnets by means of a wire 159. Thus when the slides 102 and 134 are depressed either one or two steps, electrical connection will be established between the frame 89 and the magnets 148, 115 causing the actuation of the armature lever 149 and a consequent step by step rotation of the disk 147.

120 Mounted upon the upper end of the shaft 146 is an S-shaped contact plate 160, and 130

4

pivotedly mounted upon the cross bar 89 of the frame 89 is a depending rod 161. This rod is mounted in bearings 162 and the lower end of the rod is so bent that its extremity 146 so that the terminal end of the rod will contact with the plate 160 during a portion of the revolution of the shaft 146 but will be disconnected therefrom during another portion of the rotation of the shaft. The rod 161 after it passes through the bearing 162 is bent outward as at 163 and then bent laterally as at 164 and then extends downward and again laterally as at 165 so as to engage beneath the pawl 110. It will thus be seen that when the rod 161 is rocked by contact with the plate 160, the terminal end 165 of the rod will shift the pawl 110 outward and release the slide 102, permitting the slide to move upward. Also mounted in a bearing upon the upper face of the cross bar 89 of the frame is a cranked rod 166, one end of which extends rearward and then outward beneath the portion 163 of the rod 161, and the other end of which extends immediately beneath the pawl 137. Thus also when the rod 161 is rocked by contact with the S-shaped plate 160, the angular extremity 167 will engage beneath the spring 30 pawl 137 to release it.

As before stated, the frame 89 is electrically connected to the generator or other source of power on the engine and the slides 134 and 102 are thus connected through the frame with the generator. When these slides are depressed therefore, the fingers 141 and 140 will engage with the contact members 157 and 158 and current will be transmitted to the magnet coils 148, causing a vibration of the armature 149. As soon as the S-shaped contact plate 160 has forced the end of rod 161 inward a sufficient distance, the detent pawls 110 and 137 will be forced outward, permitting the slides 102 and 134 to rise. This would break the circuit through the fingers 141 and 140 were it not for the fact that the rod 161 will now act as the conductor and carry the current from the main frame 89 downward to the contact plate 160 and from thence by the frame supporting the shaft 146 to the plate 135 and thus to the magnets. The motor will continue to be actuated therefore until the contact plate 160 moves past the arm 161^a, permitting the arm to fly back to its original position out of contact with the plate. The motor will then stop. The motor is so calculated that it will run for about five or ten seconds before the current will be entirely cut off from it.

The operation of this portion of the invention will be understood from the diagrammatic view Fig. 14. In this diagram, M designates a generator of any suitable character driven by the engine, as for in-

stance the headlight generator. This source of power, however, may be a storage battery. I do not wish to limit myself to any particular source of power. As illustrated, one side of the generator is connected by a wire 169 to a ground 170. Mounted upon the engine are three shoes 171, 172 and 173. The shoe designated 171 is the closing shoe. The shoe 172 is the danger shoe, and the shoe 173 is the clearing shoe. 75

Extending from the shoe 171 is a wire 174 which leads to the magnets 80 actuating the armature lever 84. From the shoe 172 a wire 175 extends to the magnets actuating the danger armature 86. From the shoe 173 extends a wire 176 to the magnets 81 actuating the armature 85. From the magnets 80 extends a wire 177 having therein bell magnet coils 178, this wire 177 extending to a wire 179 which is connected to the generator. This wire 177 is not connected to any light signals. From the magnet 81 extends a wire 180 which passes through the signal magnets 181 and connects with the wire 179. From the danger magnets 82 extends a wire 182 which extends to the wire 179. Thus it will be seen that each one of the three pairs of magnets actuating the armatures 84, 85 and 86 is connected on one side with the generator M and on the other side with one of the shoes, 171, 172 and 173. The bells operating in conjunction with the magnets 178 and 181 are both constructed in the same manner, the armature of each magnet carrying upon its end a clapper engaging with a gong 178^b so that upon an energizing of the magnet the armature will be drawn over and the bell struck one blow.

Also leading from the wire 179 is a wire 148^a which leads to the magnets 148, these magnets being connected to the frame 89 of the machine by means of the wires 156 and 159 as previously described. The frame 89 is connected to the wire 169 and thus to the generator by means of a wire 183. The contact 130^a is connected by means of a wire 184 to the contact 101 and the contacts 113 and 114 are connected respectively to a motor O and to a green light. The contact 113 is connected to the motor O by means of a wire 185, while the contact 114 is connected to a wire 186 which extends to a green light 182 and then extends to the wire 179. Thus when the contact member 101 is moved into engagement with the contacts 113 and 114, current will be transmitted from the frame 89 through contacts 118 and 130^a to both of these contacts and thus through wire 186 and the green light 182 to the wire 179 and the generator, and from the contact 113 to the wire 185 and so to the motor O on the air line. This motor and its connected parts will be later described.

The contacts 131 and 132 are insulated from each other. The contact 131 is con- 130

ected by means of a wire 186^a to a continuously ringing bell through the magnets 187 thereof, and from these magnets a wire 188 passes to the wire 179. From the contact 5 132 a wire 189 leads to the wire 185, and so to the brush of the motor O.

The motor O is an electric motor of any suitable character, and connected to the opposed brushes thereof are the wires 185 and 10 179. This wire 179 as previously stated, leads to one side of the generator M, while the wire 185 from the other side of the motor leads by wire 189 to the contact member 132.

15 The spindle of the air valve is designated 190. The air valve, however, is not shown. The spindle is provided with the radially arranged handle 191 (see Fig. 15) and loosely mounted upon the spindle is a gear 20 wheel 192 having projecting therefrom a stud 193 adapted to engage with the handle. Mounted in conjunction with the gear wheel 192 is a worm shaft 194 having thereon the worm 195. This is connected by a universal 25 joint at 196 with the shaft 197 of the motor O. The screw shaft 194 can be lifted out of engagement with the worm wheel 192 by means of a lever 198 connected to the screw shaft 194 by a link 199. A spring 200 is so 30 mounted and engaged with the gear wheel 192 that when the worm shaft 195 is released from its engagement with the worm wheel 192, the spring will act to return the worm wheel to its initial position and withdraw 35 the lug 193 from its engagement with the handle 191. When, however, the motor O is energized, the worm 195 will cause the wheel 192 to rotate until the lug 193 engages the handle 191, whereupon the handle 191 will 40 be rotated with the gear wheel and the spindle 190 will turn the air valve to such position as to set the brakes of the train. The worm 194 and the wheel 192 have such ratio and operate at such speed that it will take 45 between three to five seconds for the stud 193 to move from its initial position into engagement with the handle 191. In other words, it will take the same length of time after the actuation of the motor O for the 50 brakes to be set as it will for the contact plate 160 to move from its initial position to fully actuate the releasing lever or rod 161.

In order to secure a danger signal in case the wire leading from the generator or the 55 wire 183 is broken, or cut, I provide a wire 201 which leads from the wire 183 and is connected to a lamp 202 or other suitable signal and then extends to the wire 179. It will be seen that a circuit through this lamp 60 is always maintained through the wire 179, generator and wire 183.

The operation of so much of the invention as has been described is as follows: When 65 the closing shoe 171 strikes a grounded track contact for instance, a circuit is completed

from the generator in the direction of arrow along wire 179 to wire 177, through the magnet coils 178 (actuating the bell 178^b), along wire 177 to the closing magnets 80, then to wire 174 and along wire 174 to the shoe 171 through the contact to the ground, completing the circuit.

The momentary energizing of the magnets 80 will cause the armature lever 84 to be drawn downward. The pawl on the extremity of the armature lever 84 will engage the tooth 108^a and force the slide 102 down one notch until the shoulder 109 is engaged by the pawl 110. When this occurs, the finger 141 will make contact with the contact piece 157 and current will pass into the magnets 148. The armature 149 will now be vibrated, thus rotating the wheel 147, and this position of the parts will continue until the lever 161 is released by the engagement of its end 161^a with the plate 160. When this occurs, the pawl 110 is shifted from its engagement with the notch 109 and the spring returns the slide 102 to its original position. If two energizations of the closing magnet are secured by reason of the closing shoe passing over two contact switches which are grounded, then the first depression of the closing armature lever will bring the parts to the 90 position just described, and upon the second 95 depression of the lever, the pawl 88 will engage the notch 108 and depress the slide 102 to such position that the tooth 108^a will engage the pawl 111, releasing this pawl from its engagement with the shoulder 99 on the 100 slide 94, whereupon the spring will draw the slide downward, carrying the head 101 out of engagement with the contact strip 130 and into engagement with the contact fingers 113 and 114. 105

When the head 101 is in its raised position and in contact with the strip 130, current will pass from the wire 179, along the wire 186, through the white light by means of a wire 187^a to the contact finger 130, 110 and from this contact finger through the head 101 by way of wire 184 to contact strip 130^a, thence to the head 118, thence to the frame 89 of the machine, and by wire 183 back to the generator, thus completing the 115 circuit. Thus normally the white light is burning but when two actuations of the closing lever have been secured, the head 101 breaks a circuit through the white light and by coming in contact with the strips or fingers 113 and 114 a circuit will be closed in one direction through the brake motor O and in the other direction by way of wire 186 to the green light 187 and then to the wire 179, the remainder of the circuit of 120 course being completed by the wires 183 and 169 back to the generator, from the 125 frame of the machine.

If the engineer does not actuate the lever 142 within say five seconds from the time 130

that the cautionary signal or green light is shown, then the train will be brought to a stop by an actuation of the brakes. If, however, the engineer depresses the lever 142, the slide 94 will be lifted, breaking the circuit through the closing motor and the green light and again establishing a circuit through the white light, the parts being returned to their normal position.

16 If now the shoe 172 engages with a track contact which is grounded, then a circuit will be completed in the cab through the danger shoe 172, through the wire 173 to the danger magnets, then by wire 182 to the wire 179, thence to one side of the generator, and from the other side of the generator by wire 169 to the ground as at 170.

2 The actuation of the danger lever 186 will cause the depression of the slide 119. This as it moves downward will carry the shoulder 128 into engagement with the pawl 129, releasing said pawl which will permit the slide 115 to be drawn downward by spring 123, break the engagement between the head 118 and the strip 130^a and close contact between the head 118 and the contact fingers 131 and 132. From the finger 131 a circuit will be completed from the frame 89^a to wire 186 through the magnet 187 of the continuously ringing danger signal bell, and by way of wire 188 to one side of the generator by way of wire 179. At the same time a circuit will be completed also from the frame 89 by head 118 to contact finger 132, thence 30 by way of wire 189 to the air brake motor 35 O to actuate the latter. At the same time that the circuit is closed through finger 131 and through the danger signal bell, a circuit will also be closed through the wire 40 leading to the red light or danger signal and thence by wire 186 to the wire 179 and back to the motor. Thus upon a single actuation of the danger signal armature lever 186, the danger signal bell will be sounded, the red danger signal light will be displayed, and the air valve will be shifted to its closing 45 position by the motor.

It is to be noted in this connection that the motor composed of the magnets 148 and the armature 149 will operate to return the slide 102 to its original position but will not operate to return the slide 119 to its original position, its spring 124, doing this as soon as permitted by the raising of the slide 115 by actuation of lever 142. Thus the danger signal bell and the danger signal light will continue to ring and be displayed until the engineer actuates the lever 142.

If the clearing shoe 173 comes into successive contact with two grounded contact switches a circuit will then be completed through the clearing shoe 173 along wire 176 to the clearing magnets, thence by wire 180 to clearing bell 181, thence by wire 179 to generator M and thence to the ground 170.

The first actuation of the clearing armature lever will carry the slide 134 downward one step until the pawl 137 engages the shoulder 136. If now a second actuation of the armature lever is secured before the arm 165 acts to throw out the detent 137, the pawl on the arm 85 will engage the second notch 135 and move the slide 134 downward a still further distance. The bell will be sounded so as to indicate this second actuation of the armature lever 85 but no light signal is given upon this actuation of the armature lever 85. 70 75

It is particularly desirable that some record be kept to show when the engineer received signals, and the character of the signals received between the entrance of a block and the end thereof. 80

For this purpose I provide a tape designated 203 which passes over the lower bar 93 of the frame 89. This tape is mounted in any suitable manner as upon spools 204 and 205 and is actuated by clockwork so that it passes continuously across the face of the bar 93. This bar is perforated at a plurality of points. Mounted between the lateral uprights of the frame 89 and particularly between the guide rods 133 and the side bar 89^a of the frame is a needle guiding frame designated 206 and comprising side supports and transverse horizontal cross bars 207, 208 and 209. These cross bars are perforated for a plurality of needles. The needles as illustrated are five in number. The needles 210 and 211 move together and are connected to an arm 217 projecting from the slide 102. A pair of needles 213 and 214 project downward from an arm 215 projecting from the slide 134. Projecting from the slide 119 is an arm 216 carrying a needle 217. This needle 217 is located between the two pairs of needles 211, 210, 213 and 214. The needle 210 is longer than the needle 211. The needle 214 is the same length as the needle 210 and is longer than the needle 213. The needle 217 extends downward a sufficient distance so that its point is on a line with the points of the needles 211 and 212.

The operation of this recording system is as follows. When the closing shoe of the engine strikes a grounded contact, a circuit will be completed through the magnets 80 and the armature lever 84 will be depressed. This will cause a depression of the slide 102 one tooth and the pawl on the armature lever will engage the tooth 108 when it rises. This initial depression of the slide 102 will carry down with it the finger 212 and will cause the needle 210 to enter the recording tape. Therefore, the tape will show only one puncture. If, however, a second contact is engaged, a second depression of the armature 84 will be received and inasmuch as at this time the pawl on the armature is en-

gaged with the tooth 108, the slide 102 will be forced down its full distance, carrying with it the needle 211 so that a second puncture will be given to the tape in the column marked on the tape for the punctures indicating what may be termed the block closing record.

The needle 217 is designed to indicate the instant at which a train receives a danger signal. Thus when a circuit is completed through the magnets actuating the danger armature 86, this armature will be drawn downward as previously described, causing the release of the slide 115 and causing this slide to drop under the action of the spring 123. This slide 115 carries upon it the arm 216 which carries the needle 217, and this needle will puncture the record strip or tape, indicating that a danger signal has been received.

When the clearing shoe on the train reaches a grounded contact one actuation of the armature lever 85 will be received and the long needle 214 carried by the arm 215 projecting from the slide 134 will be depressed and the needle will puncture the tape. If, however, the clearing shoe passes over two grounded contacts the slide 134 will receive a two-step actuation which will cause both of the needles carried by the arm 215 to enter the tape.

The tape 200 may be supported and moved in any suitable manner either continuously or intermittently. This tape of course moves relatively slowly but in order to provide for a slight movement of the tape at the time when the needles have entered the tape, I preferably slot the bars 207, 208 and 209, and the needles being slightly resilient will give to the tape.

Preferably the tape as shown in Fig. 16 has three longitudinally extending columns printed upon it, one column, that to the left in Fig. 16, being for the closing signals, the middle column being for the danger signals and the third or right hand column being for the clearing signals. The tape is also preferably divided into time graduated sections, each of these sections being divided into spaces of one minute. Thus the perforations made by the recording needles upon the tape when taken in conjunction with the time graduations will indicate the length of time occupied by the train in passing from one end of the block to another, and will also indicate precisely the time at which the signals were received and the character of the signals.

With recording apparatus and signaling apparatus as heretofore described, it will be plain that the engineer will receive an audible as well as a visual signal indicating the condition of the block, and that in conjunction therewith a record will be kept of the signals received. This is of obvious advan-

tage to the company where it is necessary to fix the responsibility for an accident, and it is also of advantage to the engineer as after a signal has been received and recorded (which it is instantly) the engineer, if he 70 forgets what signal has been received, may look upon the tape.

It will be seen that with any form of my invention the engineer is warned visually and audibly of the condition of the block, 75 and can not escape responsibility by asserting his inability to read the track signals. Furthermore the record made by the recording needles will show absolutely whether the engineer has or has not received a certain 80 signal and whether he should or should not have brought his train to a standstill. Furthermore the engineer can not run past the signals through inadvertence for the reason that if he does not within five or ten sec- 85 90 onds depress the lever 142, the air brakes will be put on and the train brought to a standstill, at least in those cases where a cautionary or a danger signal has been given.

My improved system may be installed at a relatively small cost, the mechanism carried in the cab of the engine being compact and relatively cheap.

While I have referred to the contact shoes 95 as being mounted upon the engine itself, in practice these contact shoes will preferably be mounted beneath the tender as shown in Fig. 1. The contact shoes will ordinarily be between five and six feet long and turned 10 upward at each end so as to engage the contact switches with the least possible jar or shock.

What I claim is:

1. In an electric block signal system, the 10 combination with a grounded track contact member, of a vehicle having thereon a source of energy grounded on one side, a shoe 110 adapted to engage said track contact and electrically connected to the source of energy, an electrically actuated signal, means actuated by the engagement of the shoe with the track contact for electrically connecting the signal in circuit with the source of energy, and means operating within a predetermined time for breaking said circuit.

2. In an electric block signal system, the combination with a grounded track contact member, of a vehicle having thereon a source of energy grounded on one side, a shoe 120 adapted to engage said track contact, an electrically actuated signal, means actuated by the engagement of the shoe with the track contact for electrically connecting the signal in circuit with the source of energy, 125 and motor actuated means operating within a predetermined time for breaking said circuit.

3. In an electric block signal system, the combination with a grounded contact mem- 130

ber, of a vehicle having thereon a source of energy, a shoe adapted to engage said contact and electrically connected to the source of energy, a signal, means actuated by the engagement of the shoe with the track contact for electrically connecting the signal in circuit with the source of energy, a motor, means actuated by the operation of the motor for a predetermined time acting to break said circuit, and means for electrically connecting the motor in circuit with the source of energy upon the engagement of the said shoe with the said contact member.

4. In an electric block signal system, the combination with a grounded track contact, of a vehicle having thereon a source of energy, a shoe adapted to engage said track contact, said shoe being electrically connected to the source of energy, a signal, means actuated by the engagement of the shoe with the track contact for electrically connecting the signal in circuit with the source of energy, a motor, means actuated by an operation of the motor for a predetermined time acting to break the circuit to the signal, means actuated by the engagement of the shoe with the track contact for electrically connecting the motor to the source of energy, and means actuated by the operation of the motor for a predetermined time acting to break said circuit.

5. In an electrically actuated block signal system, the combination with normally grounded contact members, of a vehicle having thereon a source of energy, a shoe adapted to successively engage said track contacts and electrically connected to the source of energy, a magnet electrically connected in a circuit including the shoe and the source of energy, circuit closing mechanism actuated by the energizing of said magnet, a signal normally electrically connected with the source of energy and remaining so upon one actuation of said circuit closing mechanism, a second signal in a circuit adapted to be closed upon a second actuation of the circuit closing mechanism, and means for breaking the circuit through the first signal upon the closing of the circuit through the second signal.

6. In an electrically operated block signal system, the combination with normally grounded track contacts, of a vehicle having thereon a source of energy, a shoe adapted to engage said track contacts and electrically connected to the source of energy, a magnet in such circuit, a circuit closing mechanism shifted in one direction upon the energizing of said magnet, means for holding said circuit closing mechanism in a shifted position for a predetermined time and then releasing the circuit closing mechanism to permit its return to its original position, means for shifting said circuit closing mechanism a second time in continua-

tion of its first movement upon a second energizing of the magnet prior to the release of the circuit closing mechanism, and signals respectively electrically disconnected from and connected with the source of energy by the second actuation of the circuit closing mechanism.

7. In an electrically operated block signal system, the combination with normally grounded track contacts, of a vehicle having thereon a source of energy, a shoe adapted to engage said track contacts and electrically connected to the source of energy, a magnet in such circuit, a circuit closing mechanism shifted in one direction upon the energizing of said magnet, means for holding said circuit closing mechanism in a shifted position for a predetermined time and then releasing the circuit closing mechanism to permit its return to its original position, means for shifting said circuit closing mechanism a second time in continuation of its first movement upon a second energizing of the magnet prior to the release of the circuit closing mechanism, two signals, and mechanism for maintaining the electrical connection of one of said signals with the source of energy upon the initial shift of the circuit closing mechanism and for breaking the circuit through the first named signal and closing a circuit through the second named signal and the source of energy upon the further shift of the circuit closing mechanism.

8. In an electric block signal system, the combination with normally grounded track contacts, of a vehicle having thereon a source of energy, a shoe adapted to engage said track contacts and electrically connected to the source of energy, a magnet connected in circuit with the shoe and the source of energy, an armature, a circuit closing and opening device adapted to be shifted in one direction by the energizing of the magnet, a signal in a normally closed circuit with said source of energy, a signal in a normally interrupted circuit with said source of energy, means for holding the circuit closing device in its shifted position for a predetermined time after its initial shift and then releasing the circuit closing device to permit its return to its original position, and means actuated by a second energizing of the magnet within the predetermined time, shifting the circuit closing device to a position to complete a circuit through the second named signal and break the circuit through the first named signal.

9. In an electric block signal system, the combination with normally grounded track contacts, of a vehicle having thereon a source of energy, a shoe adapted to engage said track contacts and electrically connected to the source of energy, a magnet electrically connected in circuit with the shoe and source

- of energy, a circuit closing and opening device shiftable in one direction by the energizing of the magnet, means acting to return the circuit closing device to its original position, means for causing a step by step actuation of the circuit closing device upon successive energizations of the magnet, means for returning the circuit closing device to its original position within a predetermined time after the energizing of the magnet, electrically operated brake actuating mechanism, and means actuated by a shifting of the circuit closing mechanism by two successive energizations of the magnet acting to close the circuit through the brake actuating mechanism and the source of power.
10. In an electric block signal system, the combination with a track contact, of a vehicle having thereon a source of energy, a shoe adapted to engage said track contact, said shoe being electrically connected to the source of energy, a signal, means actuated by the engagement of the shoe with the track contact for electrically connecting the signal in circuit with the source of energy, and a timing mechanism for breaking said circuit.
11. In an electric block signal system, the combination with a grounded track contact, of a vehicle having thereon a source of energy, a shoe adapted to engage said track contact, said shoe being electrically connected to the source of energy, electrically operated brake actuating mechanism, means actuated by the engagement of the shoe with the track contact for electrically connecting the actuating mechanism in circuit with the source of energy, a signal, means actuated by the engagement of the shoe with the track contact for electrically connecting the signal in circuit with the source of energy, and a timing mechanism for breaking the circuits through the signal and through the brake operating means.
12. In an electric block signal system, the combination with a grounded track contact, of a vehicle having thereon a source of energy, a shoe adapted to engage said track contact, said shoe being electrically connected to the source of energy, electrically operated brake actuating mechanism, means actuated by the engagement of the shoe with
- the track contact for electrically connecting the actuating mechanism in circuit with the source of energy, a signal, means actuated by the engagement of the shoe with the track contact for electrically connecting the signal in circuit with the source of energy, time actuated means for breaking the circuit through the signal and through the brake actuating means, and manually actuatable means for breaking said circuit.
13. In an electric block signal system, the combination with a grounded track contact, of a vehicle having thereon a source of energy, a shoe adapted to engage said track contact, said shoe being electrically connected to the source of energy, an electric motor, a brake applying mechanism, means operated by the motor for actuating said brake applying mechanism after a predetermined number of rotations of the motor, means actuated by the engagement of the shoe with the track contact for electrically connecting the said motor in circuit with the source of energy, and manually actuatable means for disconnecting said motor from the brake mechanism.
14. In a track signaling system, the combination with a grounded track contact, of a vehicle having thereon a source of energy grounded on one side, a shoe adapted to engage said track contact, a step by step circuit closing mechanism actuated by the closing of a circuit between the shoe and the source of energy, a signal adapted to be actuated by the actuation of the circuit closing mechanism, a pair of punches operatively connected to the step by step circuit closing mechanism, said punches being of different length, a tape with which said punches are adapted to coact, and means for forcing one of the punches into the tape upon a one-step actuation of the circuit closing mechanism and for forcing both punches into the tape upon a two-step actuation of the circuit closing mechanism.

In testimony whereof I affix my signature in presence of two witnesses.

MARSENA R. JULIAN. [L.S.]
